(57) **CLAIM**

The ornamental design for a sealing member as shown and described.

DESCRIPTION

FIG. 1 is a top perspective view of another embodiment of a sealing member in a wrapped position showing our new design;

FIG. 2 is front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the transparent sealing member in an elongated position;

FIG. 9 is a top view of the transparent sealing member in the elongated position;

FIG. 10 is a top perspective view of another embodiment of a transparent sealing member in a wrapped position showing our new design;

FIG. 11 is front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a perspective view of the transparent sealing member in an elongated position; and,

FIG. 18 is a top view of the transparent sealing member in the elongated position.

The dash-dash broken lines shown in the drawings illustrate environmental subject matter and form no part of the claimed design. The dash-dot-dash broken lines indicate the presence of perforations in the sealing member.

1 Claim, 12 Drawing Sheets
